SELF-LINE CLEANING PULLEY

William H. Zimbalist, Brooklyn, N. Y.

Application July 3, 1948, Serial No. 37,019

8 Claims. (Cl. 15—256.6)

1

This invention relates to clothes line pulleys and, particularly, to devices of this type and kind, including as part of the housing structure of the pulley, means for cleaning the line in the operation of moving the line around or through the pulley. The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a longitudinal sectional view through a pulley made according to my invention, indicating a clothes line in dot and dash lines.

Fig. 2 is a section on the line 2—2 of Fig. 1 with part of the construction shown in elevation and with parts broken away.

Fig. 3 is a section on the line 3—3 of Fig. 1; and

Fig. 4 is a detailed view of one of the wiper elements which I employ, detached.

In the construction shown, I provide a pulley which is fashioned from two substantially similar casing parts 10, 10', each part having inwardly set hub portions 11, 11' for support of the pulley axis 12 in the form of a rivet pin. The casing parts, when assembled, by riveting together two projecting flaps or flanges 13 as by the rivet 14, and by turning-over hook flange portions, as at 15, form a disc-type casing having two tubular admission and discharge extensions, as at 16 and 17, as clearly illustrated in Fig. 1 of the drawing, and also shown in Fig. 3 of the drawing. The hook-shaped flanges 15 are formed on wall portions 18, which join the tubular portions 17, as clearly seen in Fig. 3 of the drawing and these wall portions are pressed outwardly to form a longitudinal channel 19 for purposes later described.

Mounted on the rivet pin 14 is a coupling or hanger loop 20.

Arranged around the axis 12 are a series of ball bearings 21, note Fig. 1, which are arranged between the separate parts 22, 22' of the pulley which is disposed in the casing, these pulley parts being secured together by welding, as indicated at 23 in Fig. 1 of the drawing. In conjunction with the casing or the separate parts 10, 10' thereof, still more particularly, in connection with the tubular extensions 16, 17 are two similar wiper elements 24, each element comprising a twisted wire strand having a long mounting end 25 and a short mounting end 26, the intermediate portion of the strand having a suitable brush body 27 of ring-like or annular construction. In other words, that part of the twisted strand, on

2

which the brush body is arranged, is shaped into circular form, so as to provide an opening 28 centrally of the brush body which is preferably smaller in diameter than the outside diameter of the clothes line to be passed therethrough, which clothes line is indicated in dot-dash lines at 29 in Fig. 1 of the drawing and also indicated in Fig. 3 of the drawing. In assembling the parts of the pulley casing, two of the elements 24 are arranged between the walls 18 in the channel 19 with the long ends 25 of the elements overlapping each other, as clearly seen in Fig. 3 of the drawing. In final assemblage of the casing parts, the walls 18 are preferably crimped together, as indicated at 30 in Fig. 3, so as to securely bind the elements 24 in position to maintain the openings 28 in suitable centralized position within the tubular portions 16 and 17 of the casing.

With this construction, it will be apparent that, as the clothes line 29 is passed around the pulley, the clothes line will be frictionally passed through the circular or ring-like wiper elements, or brush bodies 27 of the wiper elements and any deposits that may be present on the line will be removed and the line kept clean for the intended use. It will be recommended that, preparatory to using the line, the line will be run through the pulleys a number of times for this purpose.

By constructing both parts of the casing and the pulley of similarly shaped members and by utilizing two wiper elements of similar construction, the cost of producing the entire device is materially simplified. Thus the pulley can be sold at a relatively reasonable price. While in the present construction, I have illustrated certain types of wiper or cleaner elements, the structure of these elements may be modified to suit the intended uses, particularly in pulleys of any type or kind. In some instances, where a strand-like body is passed around a pulley member, these elements may be utilized for any purpose consistent with the results that may be desired.

Having fully described my invention, what I claim as new and desire to secure by Letters Patent is:

1. A clothes line cleaner comprising two substantially similar casing parts forming a hollow body, in which a pulley is mounted for free rotation, tubular projections on said body, the casing parts having abutting wall portions between said tubular projections, said wall portions having registering recesses on adjacent surfaces thereof opening into said tubular projections, wiper elements arranged in the tubular projections and having overlapped mounting ends dis-

posed in said recesses, means securing the casing parts together, and means retaining the mounting ends of said elements within and against displacement from said recesses.

2. A clothes line cleaner comprising two substantially similar casing parts forming a hollow body, in which a pulley is mounted for free rotation, tubular projections on said body, the casing parts having abutting wall portions between said tubular projections, said wall portions having registering recesses on adjacent surfaces thereof opening into said tubular projections, wiper elements arranged in the tubular projections and having overlapped mounting ends disposed in said recesses, means securing the casing parts together, means retaining the mounting ends of said elements within and against displacement from said recesses, and said last named means comprising indentures on the wall portions of the casing parts engaging overlapped portions of the mounting ends of said elements.

3. A clothes line cleaner comprising two substantially similar casing parts forming a hollow body, in which a pulley is mounted for free rotation, tubular projections on said body, the casing parts having abutting wall portions between said tubular projections, said wall portions having registering recesses on adjacent surfaces thereof opening into said tubular projections, wiper elements arranged in the tubular projections and having overlapped mounting ends disposed in said recesses, means securing the casing parts together, means retaining the mounting ends of said elements within and against displacement from said recesses, said last named means comprising indentures on the wall portions of the casing parts engaging overlapped portions of the mounting ends of said elements, and said elements comprising brush bodies.

4. A clothes line cleaner comprising two substantially similar casing parts forming a hollow body, in which a pulley is mounted for free rotation, tubular projections on said body, the casing parts having abutting wall portions between said tubular projections, said wall portions having registering recesses on adjacent surfaces thereof opening into said tubular projections, wiper elements arranged in the tubular projections and having overlapped mounting ends disposed in said recesses, means securing the casing parts together, means retaining the mounting ends of said elements within and against displacement from said recesses, said last named means comprising indentures on the wall portions of the casing parts engaging overlapped portions of the mounting ends of said elements, and said elements comprising brush bodies of substantially circular formation.

5. A clothes line cleaner comprising two substantially similar casing parts forming a hollow body, in which a pulley is mounted for free rotation, tubular projections on said body, the casing parts having abutting wall portions between said tubular projections, said wall portions having registering recesses on adjacent surfaces thereof opening into said tubular projections, wiper elements arranged in the tubular projections and having overlapped mounting ends disposed in said recesses, means securing the casing parts together, means retaining the mounting ends of said elements within and against displacement from said recesses, and said elements comprising ring bodies disposed within said tubular projections.

6. A pulley frame comprising similar casing parts, a pulley rotatably mounted in said frame, upper and lower portions of the frame having tubular portions in alignment with opposed peripheral portions of said pulley, a ring body of yielding material in one of said tubular portions, and means retaining said ring body against displacement from said frame.

7. A pulley frame comprising similar casing parts, a pulley rotatably mounted in said frame, upper and lower portions of the frame having tubular portions in alignment with opposed peripheral portions of said pulley, a ring body of yielding material in one of said tubular portions, means retaining said ring body against displacement from said frame, and said means comprising a wire strand clamped between the casing parts.

8. A pulley frame comprising a pair of similar casing parts, a pulley freely rotatable within the casing parts, means securing the casing parts together, upper and lower portions of the assembled casing parts having tubular portions in alignment

40 with opposed peripheral portions of said pulley, a ring body arranged within each of said tubular portions, each of said bodies having means arranged and clamped between the casing parts for retaining said bodies against displacement from the tubular portions, and said last named means comprising mounting ends overlapped one with respect to the other within the casing parts.

WILLIAM H. ZIMBALIST.
